FOLDING ELECTRIC STOVE

Constantine P. Lent, New York, N. Y.

Application February 11, 1936, Serial No. 63,304

9 Claims. (Cl. 219—19)

This invention relates to the class of electric stoves and particularly to a type of folding electric stove.

One object of the invention is to provide an electric stove comprising two separate electric heating elements mounted inside a container resembling a suitcase or travelling case, the latter having two hinged sections which connect together when folded.

10 A further object of this invention is to provide an electric stove that is comparatively simple of manufacture and safe to operate.

A further object is to provide a folding stove having means to enclose all operating parts, such as heating elements, wires, switches and the like within said container when the latter is folded or closed up.

15 A further object is to provide space within said container for the storing of utensils when said container is folded up and not in use.

20 Further objects will be seen as the description of the invention proceeds.

Referring to the drawing:

Fig. 1 is a plan view of the folding stove in 25 open position.

Fig. 2 is a section through the stove on a line 2—2 of Fig. 1, showing one hinged side of said stove in section and an exterior view of the opposite side section. There is also shown the wire wound slidable wire connection extending across 30 from one side section to the opposite side section thereof.

Fig. 3 is an outside view of the stove when in a folded or closed position.

35 Fig. 4 is a diagrammatic view illustrating the wire connections of both heating elements in the stove aforesaid.

Fig. 5 is a section on a line 5—5 of Fig. 1 showing the manner of protecting the wire connection 40 by means of a coiled spring reinforcement.

Referring to Fig. 1, the numeral 18 is the body of the folding stove proper. Said stove consists of a folding side section or member 11 and an opposite side section or member 12.

45 The side section 11 and also section 12 have a flanged box like form, each section having a bottom 13 and sides 14, 15, 16, and 17. The aforesaid sides of the box 11 are preferably formed up of a solid piece of sheet metal. As an alternative 50 method of manufacture the said sheet metal may be bent up and the corners 17^b spot welded with angle iron reinforcements.

A top plate or tray 18 having upwardly extending side sections 19, 20, 21, and 22 is set over 55 the open portion of the box sections 11 and 12.

The top plate 18 is provided with a flanged opening 23 into which the flange 24 projects below the top surface 25 of the plate 18 and forms a step 26 as shown in Fig. 2. A heating element 27 is mounted inside the opening 23 and is held in place by means of the screw 28 which is screwed into a W-shaped bracket support 29. The said bracket support serves to support the top plate 18 and preventing the same from sagging by means of the protruding sides 30. 10

The top plate 18 or tray which is rectangular in shape is either held in place by means of screws 31 or spot welded to the body of the side sections 11 and 12. The said top plate is sunk below the level of the top edge of the respective 15 side sections 11 and 12.

A switch 32 is mounted in convenient position on the top plate 18. The switch 32 is provided with a shield plate having marks affixed thereon. Such marks may read "Off" and "On" 20 indicating whether the switch is on "on" or "off" position. In the event the switch 32 is of the variable type, the readings on the shield plate will correspond to the settings of said switch. The readings aforesaid may indicate "Off", "High", 25 "Med", and "Low" setting positions. A switch 32^a similar to switch 32 is provided in section 12 to switch current on and off for the heating element 27^a. The switches 32 and 32^a are mounted in position below the level of the top edge of the 30 respective sections 11 and 12.

The power wire 33 is connected to the stove heater element through an insulated opening 35. A reinforced spring 34 is loosely wound around the wire for added flexibility and protection 35 against contact or abrasion.

To facilitate electrical connection from one side section to the opposite side section of said stove there is provided the wire wound insulated wire connection 37. One terminal of said wire connection enters the box section 11 at the insulated opening designated as 38 (see Fig. 5) and the opposite terminal of said wire connection enters the box section 12 through the insulated opening 39. The wire wound spring reinforcement 40 is wound loosely around the insulated wire connection to protect said wire connection from wear or abrasion. The spring reinforcement 40 is provided with insulated flanged terminals 41 and 42 as shown in Figs. 3 and 5. 45

When said adjacent sections 11 and 12 are folded, the wire wound reinforcement section 40 of the wire connection slides through the bushing 38 (see Fig. 5) and into the inside of side section 11 as shown in Fig. 2, and when said 50

55

adjacent sections 11 and 12 are opened the wire wound reinforcement 40 slides outwardly through the bushing 38 aforesaid.

- Referring to Fig. 4, the stove heating elements 5 27 and 27^a are wired in parallel. The main lead A multiplies into leads B and C. The current from the outside leads A flows in multiple through the lead B to switch 32 and from said switch through wire lead D to the heating element 27. Likewise, 10 the current from the main lead A flows through lead C, wire connection 37 to the switch 32^a and from thence to the heating element 27^a. Both heating elements work independently of each other.
- 15 Insulated legs or the like are provided to prevent possible short circuit and also from scratching surfaces upon which the stove may rest.

There are also provided ventilating vents 44 which serve to reduce the temperature inside the 20 stove and underneath the heating elements.

The stove box sections 11 and 12 can be filled up with some manner of insulated material such as asbestos or the like to prevent the overheating of the respective bottoms 13 of said box section.

25 Sufficient space is provided between the tray tops 18 in the event that the stove container side sections are folded to accommodate as storage a toasting rack or broiling pan, the latter being utilizable with this type of heater when the said 30 stove is opened for operation.

A carrying handle 45 and lock 46 are provided as shown. Hinges 47 and 48 are preferably spot welded to the sides 17, 17^a of the side box containers 11 and 12. The hinges aforesaid may 35 also be screwed on to the side sections aforesaid.

As stated, the spring reinforcement is provided to protect the wire connection from wear or abrasion. Said spring reinforcement slides out of the box members when opened and said spring 40 slides inward into said box members when said box members are folded together.

In this manner the wire connection may be contained within the box members when the latter are closed, and as a consequence substantial 45 protection to said wire connection is afforded when said stove is folded up and in shape to be carried by hand or is being transported.

It is understood that modifications from the foregoing description are possible, and I therefore 50 do not desire to limit myself to the strict interpretation of the text aforesaid, but limiting myself only by the scope of the appended claims.

What I claim is:

1. In a device of the class described comprising 55 an electric stove having adjacent boxlike members hinged together, each member containing heating elements; an electric wire service outlet connected into one of said boxlike members; a flexibly slideable connection included in the 60 circuit with said service outlet, a wire winding loosely surrounding said wire connection, said flexible connection serving as a current lead for supplying current to the heating element in the box like member adjacent to the member into 65 which the service wire is connected, said electric connection being housed when said adjacent boxlike members are folded together.

2. In a device of the class described comprising 70 an electric stove having adjacent boxlike members hinged together, each of said members containing electric heating elements, a wire service outlet connected into one of said members; a flexibly slideable connection included in the circuit with said service outlet, a wire winding loosely 75 surrounding said wire connection, said flexibly

slidable connection serving as a lead for supplying current to the heating element in the boxlike member adjacent to the member into which the service wire is connected, said electrical connection being housed when said adjacent boxlike members are folded together; and individual electric switches included in said circuit for independently connecting or disconnecting each of said electric heating elements to the service outlet aforesaid.

3. An electric stove of the class described comprising adjacent hinged boxlike members; a tray inside each of said members, said tray affixed below the top edge of each of said boxlike members; a flanged opening in each of said trays, a heating element in each of said openings, said elements held rigidly inside said openings through the medium of a bracket underneath each of said trays and said heating elements, a flexible wire wound electric wire connection for one of said 20 heating elements, mounted across said members, said wire connection being slidably housed when said boxlike members are folded together.

4. In a device of the class described comprising a portable electric oven having two adjacent 25 hinged boxlike members; electric heating elements included in each of said members; a flexible wire wound insulated wire connection slidably mounted between said hinged members, said wire connection being housed inside said box 30 members when said boxlike members are closed; current controlling means for each of said heating elements contained within each of said boxlike members and means for locking and carrying said oven when said boxlike members are closed.

5. In a device of the class described comprising adjacent hinged boxlike members, a tray affixed inside of each of said members, and below the top edge thereof; a flanged opening in each of said trays, a heating element in each of said 40 openings, a bracket support secured underneath each of said trays and heating elements mounted on said trays, a switch mounted on each of said trays, and a slidably wire wound insulated wire 45 connection between said boxlike members for the purpose of electrically connecting said heating elements in the adjacent hinged members with an electric service outlet as set forth.

6. In a portable electric stove comprising adjacent hinged members, each of said members having 50 heating elements therein, a service outlet connected to one of said members, branch circuits leading from said circuit to each of said heating elements, one of said branches having a slideable wire wound insulated lead, said lead contained within the inner area of said adjacent members whereby said lead may be slidably inserted and held within the inside space of said adjacent members when said members are closed, and said lead being extended when said adjacent members 55 are opened and in position for use.

7. The structure as set forth in claim 6—and switching means in each of said branch circuits for connecting and disconnecting service current flowing therein, said switching means 65 contained within the inner area of said hinged members whereby said switching means are internally housed within said hinged members when said hinged members are folded.

8. In a folding electric stove having two adjacent hinged members each of said members comprising a boxlike form having sides, a bottom and an open top, a flanged tray of rectangular contour inserted inside each of said hinged members, the bottom section of said flanged trays 75

being below the open top edge of said hinged members; openings included in the bottom section of said flanged trays, said openings having electric heating elements mounted therein; a wire 5 lead for supplying current directly to one of said heating elements, a slidably mounted wire connection included in the circuit with said lead wire, said slidably mounted wire connection also connected to the opposite adjacent heating ele- 10 ment to supply current thereto; and a latch and a carrying handle mounted on said hinged members for locking or securing said hinged members together thereby facilitating the carrying of the stove aforesaid.

15 9. In a folding electric stove having two ad-

jacent hinged members, each of said members having a flangelike form, each of said members having a flangelike tray fitted therein, said flanged shaping in said trays being smaller in size than the flanged shaping of said hinged mem- 5 bers, said flangelike trays having openings into which electric heating elements are mounted; a bracket mounted underneath each of said heating elements; heat insulating material such as asbestos or the like held in the space provided 10 between said trays and the bottom of said hinged members; and means for conveying current to said heating elements contained in the adjacent hinged members aforesaid.
